(57) **CLAIM**
The ornamental design for a chair, as shown.

DESCRIPTION

FIG. 1 is a front perspective view of a chair according to our new design;

FIG. 2 is a front view thereof;

FIG. 3 is a rear view thereof;

FIG. 4 is a right side view thereof;

FIG. 5 is a left side view thereof; and

FIG. 6 is a top view thereof.

FIG. 7 is a front perspective view of a chair end according to another embodiment of our new design;

FIG. 8 is a front view thereof;

FIG. 9 is a rear view thereof;

FIG. 10 is a right side view thereof; and,

FIG. 11 is a top view thereof.

1 Claim, 6 Drawing Sheets
